UNITED STATES PATENT OFFICE.

JOHN SCHADE, JR., OF BROOKLYN, NEW YORK, ASSIGNOR TO NATIONAL BLANK BOOK COMPANY, OF HOLYOKE, MASSACHUSETTS, A CORPORATION OF MASSACHUSETTS.

SPRING-CLIP FOR TEMPORARY BINDERS.

1,125,403.

Specification of Letters Patent. Patented Jan. 19, 1915.

Application filed April 16, 1914. Serial No. 832,233.

To all whom it may concern:

Be it known that I, JOHN SCHADE, Jr., a citizen of the United States, residing in the city of Brooklyn, county of Kings, State of New York, have invented certain new and useful Improvements in Spring-Clips for Temporary Binders; and I do declare the following to be a full, clear, and exact description of the invention, such as will enable others skilled in the art to which it appertains to make and use the same.

This invention relates to certain new and useful improvements in temporary binder clips, and relates more particularly to binders of the type which hold the loose leaves or other matter to be bound, by spring clips.

The primary object of the invention is to provide an improved clip in which maximum tension of the spring on the jaws is obtained, and in which the spring will effectively hold the jaws in open position, when the binder is opened to receive or enable leaves to be removed.

Further the invention aims to provide a clip in which the spring has an improved mounting that acts to effectively retain the spring in position in the opening and closing movements of the jaws.

Still further, the invention aims to provide a simplified means for connecting the jaws in which the pivotal connection or pin is disposed in close proximity to the under face of the arch of the spring to thereby derive maximum holding efficiency from the spring when the jaws occupy closed position.

In the drawings: Figure 1 is an end elevation of a binder equipped with clips constructed in accordance with the present invention; Fig. 2 is a top plan view of one of the clips in open position; Fig. 3 is a section on the line 3—3 of Fig. 2, showing the clip in closed position; and Fig. 4 is a top plan view of the clip in closed position.

In proceeding in accordance with the present invention, a pair of jaws 1 are employed which are preferably formed of sheet metal strengthened by longitudinal corrugations 2. Each of the jaws 1, has a pair of

ears 3 at one end thereof, the ears overlapping and being pivotally connected by a pin 4, which latter is common to all four of the ears. The upper end portions of the jaws are curved or extended inwardly toward each other at 5, so that their free edges form stops

6, the stops 6, of the jaws being for engagement with the upper side of the ear of the opposite jaw, as depicted in Fig. 2 of the drawings, whereby it will be seen that the jaws are positively restricted in the opening movements. Each jaw has a pair of outwardly projecting nubs 7, which are preferably struck-out from the jaws and incline downwardly with respect thereto as shown in Fig. 3 of the drawings. The nubs 7, are located in such position that their noses engage the inner faces of the end portions of the C-shaped spring 8, when the jaws are in closed position, and they have their under faces engaging the inner faces of the end portions of the spring when the jaws occupy open position, as depicted in Fig. 1, of the drawings. The nubs act to provide bearings for the spring in the opening and closing movements thereof, and by virtue of the spring ends engaging the under or outer faces of the nubs, when the jaws occupy open position, it will be seen that the jaws are thereby securely held in open position, since the spring ends which are now above the pivotal connections of the jaws tend to draw the nubs together, as is apparent from Fig. 1, of the drawings. When the jaws are closed, the pin 4 occupies a position directly beneath and in close relation to the highest point of the arc of the spring, which thus enables maximum action of the spring, in retaining the jaws closed, to be obtained, which action is accentuated by the fact that the ends of the springs are disposed considerably below the pivotal connections of the jaws. From Figs. 1 and 3 of the drawings, it will further be seen that the pivotal connections of the jaws move from points considerably below the ends of the spring, when the jaws are open, to points considerably above the pivotal connections when the jaws are closed, which effects superior holding effectiveness of the jaws. In other words the pivotal connections move on opposite sides of the dead center which latter is reached during the opening and closing movements of the jaws.

What is claimed is:

In a temporary binder clip, a pair of jaws each having a pair of ears at their outer ends, a pin pivotally connecting the ears, the portions of the jaws at said outer ends thereof being bent inwardly toward each other to form stops, the stop of one jaw engaging

with the outer side edge of the adjacent ear of the other jaw when the jaws are open, nubs on the jaws between the ears and the free ends of the jaws, which nubs extend at 5 an incline toward the free ends of the jaws, and a C-shaped spring having the free ends thereof engaged with the free end edges of the nubs and adapted to have their under faces engage the inner faces of the free ends

of the spring when the jaws occupy open 10 position.

In testimony whereof I affix my signature in presence of two witnesses.

JOHN SCHADE, JR.
